UNITED STATES PATENT OFFICE.

JOSEPH STREMEL, OF SPOKANE, WASHINGTON, ASSIGNOR OF ONE-HALF TO KATHERINE SCHOMMERS, OF SPOKANE, WASHINGTON.

TOY.

1,314,614.

Specification of Letters Patent.

Patented Sept. 2, 1919.

Application filed June 5, 1919. Serial No. 301,881.

To all whom it may concern:

Be it known that I, JOSEPH STREMEL, a citizen of the United States, residing at Spokane, in the county of Spokane and State 5 of Washington, have invented certain new and useful Improvements in Toys, of which the following is a specification.

The present invention relates to improvements in toys and involves a device manually operable to produce mechanical movement with a succession of hammer blows and accompanying noise from sound producing devices.

The primary object of the invention is the 15 provision of a novel toy for children, or for older folks on a noise producing occasion of jollity, which will combine an attractive mechanical movement with a striking noise making device to create interest and amusement as well as entertainment, and the invention consists in certain novel combinations and arrangements of parts as will be hereinafter pointed out and claimed.

In the accompanying drawings one complete example of the physical embodiment 25 of the invention is illustrated, the parts being combined and arranged according to the best mode I have so far devised for the practical application of the principles of the 30 invention.

Figure 1 is a front elevation view of the toy or device embodying the invention.

Fig. 2 is an edge view of the bar carrying the sound producing devices which are illustrated thereon.

Fig. 3 is a view showing the two actuating bars, broken away, and showing in enlarged form the sound producing devices.

In the preferred form of the invention as 40 illustrated in the drawings I employ a pair of parallel actuating bars 1 and 2 which may be made of wood, metal, or other suitable material, and the free ends of the rods project somewhat beyond the operating ends of 45 the complementary rods and are equipped with hand holds or knobs 3, 3 so that the device may be held in both hands by grasping a knob in each hand and holding the device in front of the person operating it.

At their ends the rods or bars 1 and 2 are 50 pivotally linked together, the pivot points being indicated at 4, 5, 6 and 7, and the pivotal connecting members being indicated as 8 and 9. The pivotal members are preferably of metal and fashioned in the form of 55 a man, each being provided with a hammer or tappet 10 held uplifted, in position to strike, the form of the man and the hammer and handle being an integral member, and the member in each case forming a piv- 60 otal link between the parallel bars. Thus when the knobs are grasped, each in a hand, by pushing and pulling the bars in opposite directions, but simultaneously, they are brought into closer parallelism and then sep- 65 arated with the result that the respective men are caused to alternately swing bodily on their pivots 4 and 6 on the bar 2, toward and away from each other and the center of the toy, giving the appearance of striking 70 successive and alternate blows with their hammers. The swinging hammers or tappets are designed to co-act with a pair of star wheels 11 and 12, fixed on their axles 13 that are journaled in and extend through the 75 actuating bar 2, and the wheels which are preferably of metal have their teeth meshing so that they are turned in opposite di- 80 rections in unison by the intermittent and successive blows from the hammer or tappets on their teeth. Preferably the wheels are highly colored or otherwise decorated so that their movement and rotation may readily be observed and form an attractive fea- 85 ture of the toy.

The star wheels are held with stability and their movement retarded by the presence of a friction device in the form of a sounding feature involving the utilization of a pair of cam wheels or rack wheels 14 and 15 on the star wheel axles 13, and located at the side of the bar 2 opposite these wheels. The rack teeth or cams are fashioned on the outer face of the rack wheels, and the wheels are of metal, and each provided with a re- 90 silient detent as 16 and 17 bearing with frictional contact on its rack wheel and tending to retard its movement. These detents 95

are designed to make a clicking noise as the rack wheels pass under them, and to enhance the clicking sound each detent has a sound box or diaphragm, as 18 and 19 secured to the bar 2, the detent being of course fixed to its sound diaphragm. In the drawings the sound boxes are indicated as metallic disks, corrugated, with concentric circles, and the resilient detents are fastened at the outer faces of the diaphragms. Other forms of sounding devices may be employed, and other changes may be made, as for instance the outline of the striking members may be varied to imitate other persons, or things, or animals, and the different parts of the device may be made up of any suitable material, the essential features of the device being the oppositely reciprocable parallel actuating bars for the striking members whose reciprocating movement is converted into rotary movement of the rack wheels with the consequent production of sound as the wheels pass under their spring or resilient detents.

Copies of this patent may be obtained for five cents each, by addressing the "Commissioner of Patents, Washington, D. C."

What I claim is—

1. In a sounding toy, the combination 25 with the pair of oppositely reciprocable parallel bars and a pair of spaced striking members pivotally connecting them, a pair of intermeshing star wheels journaled in one bar between the striking members and adapted 30 for co-action with the striking members, a rack wheel rigid with each star wheel and a spring detent frictionally engaging each rack wheel to produce a sound, as described.

2. In a sounding toy, the combination with 35 the pair of oppositely reciprocable parallel bars and their pivotal striking members, of a pair of intermediate intermeshing star wheels having axles journaled in one bar and each axle having a ratchet wheel thereon, a pair of sound boxes fixed on the wheel supporting bar, and a resilient detent on each box to co-act with a ratchet wheel to produce sound as described.

In testimony whereof I affix my signature. 45
JOSEPH STREMEL.
